US00D563397S

(12) **United States Design Patent** (10) **Patent No.:** **US D563,397 S**
Oliver (45) **Date of Patent:** **** Mar. 4, 2008**

(54) **RADIO FREQUENCY IDENTIFICATION TAG ANTENNA ASSEMBLY**(75) Inventor: **Ronald A. Oliver**, Seattle, WA (US)(73) Assignee: **Impinj, Inc.**, Seattle, WA (US)(**) Term: **14 Years**(21) Appl. No.: **29/285,844**(22) Filed: **Apr. 11, 2007****Related U.S. Application Data**

(60) Division of application No. 29/220,493, filed on Dec. 30, 2004, now abandoned, which is a continuation-in-part of application No. 10/812,493, filed on Mar. 29, 2004, now abandoned, and a continuation-in-part of application No. 10/815,474, filed on Mar. 31, 2004, now abandoned.

(51) **LOC (8) Cl.** ..... **14-03**(52) **U.S. Cl.** **D14/230**

(58) **Field of Classification Search** D14/138, D14/230-238, 299, 358; D12/42, 43; 343/700 R-705, 343/871-908, 795, 840, 711-713, 819, 846; 455/90.2, 90.3, 91, 128, 269, 344, 347, 562.1

See application file for complete search history.

Primary Examiner—Stella M. Reid*Assistant Examiner*—John Windmuller(74) *Attorney, Agent, or Firm*—Thelen Reid Brown Raysman & Steiner LLP; David B. Ritchie(57) **CLAIM**

The ornamental design for a radio frequency identification tag antenna assembly, as shown and described.

DESCRIPTION

The FIGURE is a top plan view of a radio frequency identification tag antenna assembly showing my new design.
